LASTING MACHINE

Erastus E. Winkley, Lynn, Mass., assignor to
 United Shoe Machinery Corporation, Borough
 of Flemington, N. J., a corporation of New Jersey

Application December 2, 1938, Serial No. 243,614

34 Claims.

(Cl. 12—12)

This invention relates to lasting machines, and is herein illustrated as embodied in a machine of the bed type having means movable by the operator to last the sides of a shoe from its toe-end portion to its heel-end portion. It is to be understood, however, that the invention in various novel and useful aspects is not limited to a machine which operates in those particular locations on a shoe or on as much of a shoe as herein shown, and that it is also not limited to a machine having lasting means movable by the operator as distinguished from a power-operated machine. The machine herein shown is intended particularly for use in lasting shoes with adhesive, but in various aspects the utility of the invention is not dependent upon the character of the means whereby the margin of the upper is secured in lasted position.

For the purposes in view, the invention, in one aspect, provides a novel construction and arrangement of lasting devices for laying the margin of the upper inwardly over the bottom of the last at the opposite sides of the forepart, shank and waist portions of the shoe respectively, the term "waist portion" being used herein to refer to that portion of the shoe where the side edges of the shoe bottom curve inward lengthwise of the shoe heelwardly of the ball line. In view of such inward curvature of the edges of the shoe bottom, the waist-lasting devices, as herein illustrated, are movable laterally of the shoe in different directions than the forepart and shank-lasting devices with predetermined components of movement lengthwise of the shoe toward its toe end. In accordance with a further characteristic of the construction shown the several lasting devices are all movable about axes extending heightwise of the shoe in operating on the shoe, the forepart-lasting devices being movable each about an axis located opposite the toe-end face of the shoe, the shank-lasting devices each about an axis substantially opposite its heel-end face, and the waist-lasting devices about axes substantially opposite the sides of the toe at such distances from the shoe that these devices have components of movement lengthwise of the shoe as above described. For purposes of manual operation the several devices are supported by hand levers arranged for convenient use by the operator in his working position at the front of the machine. To adapt the machine for use with the best results on shoes of different styles and sizes, each of the lasting devices, as herein illustrated, comprises a plurality of overlaying members arranged in a series lengthwise of the edge

of the shoe bottom and relatively adjustable in accordance with the lengthwise contour of the shoe bottom, the members also being yieldable relatively to one another heightwise of the shoe in operating on the shoe. While the machine herein shown is thus provided with devices for lasting the forepart, shank and waist portions of the shoe, it will be recognized that it is within the scope of the invention to provide devices for lasting one or more of these different portions.

In another aspect, the invention relates more particularly to the construction of the lasting devices. In the machine herein shown each of the above-mentioned overlaying members comprises a leaf spring which acts as a wiper on the margin of the upper, the spring being reversely curved a plurality of times to provide a series of inwardly and outwardly extending portions spaced from one another heightwise of the shoe to increase the yieldability of the wiper. Approximately 20 the same amount of pressure will accordingly be applied to the margin of the upper on the shoe bottom by different wipers, even though they may not have been relatively adjusted preliminarily in accurate conformity to the contour of the shoe bottom. To permit relative adjustment of wipers which are substantially contiguous to one another by turning them about axes extending lengthwise thereof transversely of the edge of the shoe bottom, the construction shown is further such that each wiper formed as above described decreases progressively in width heightwise of the shoe in a direction away from the shoe bottom.

Since lasts of different styles or sizes may vary in height, the invention further provides novel means for determining the position of each last and shoe heightwise relatively to the lasting means by contact with the bottom of the shoe. For this purpose, in the machine herein shown, a height gage is movable downwardly by a treadle from an initial retracted position to gaging position, and by the same treadle also a work support is moved upwardly to carry the shoe into contact with the gage. To permit the movement of the work support to be completed by the treadle after the gage has arrived at the limit of its movement, as is desirable in view of differences in the heights of different lasts, the treadle in the construction shown is mounted on a yieldable fulcrum. The machine is further provided with means for locking the work support against retractive movement from the position determined by the gage, while permitting the gage to be retracted from the shoe upon release of the treadle.

The above and other features of the invention, including various novel details of construction and combinations of parts, will now be more particularly described with reference to the accompanying drawings and thereafter pointed out in the claims.

In the drawings,

Fig. 1 is a view in left-hand side elevation of a machine in which the invention is embodied, with portions of the structure broken away, the parts being shown in the positions which they occupy when the lasting devices are over the shoe bottom;

Fig. 2 is a plan view of the machine with the parts in the same positions as illustrated in Fig. 1;

Fig. 3 is a view similar to Fig. 1 of a portion of the structure there shown, but illustrating the positions of the parts when the height gage is in its operative position;

Fig. 4 is a perspective view of a portion of one of the forepart-lasting devices;

Fig. 5 is a plan view of a portion of one of the waist-lasting devices;

Fig. 6 is a section on the line VI—VI of Fig. 2; and

Fig. 7 is a section on the line VII—VII of Fig. 2.

The last and its shoe materials are mounted for the lasting operation on a work support including a pin 2 which enters the spindle hole in the heel end of the last and a toe rest 4 which engages the top of the forepart of the shoe upper. The pin 2 is fast on a block 6 pivotally mounted on a pin 8 carried by a slide 10 which is movable in directions lengthwise of the shoe along guideways 12 formed in opposite sides of a carrier 14. A spring 16 mounted on the slide 10 tends to swing the block 6 about the pin 8 in the direction to press the forepart of the shoe down on the toe rest 4 to assist in holding the shoe in position for the lasting operation. Extending downwardly from the toe rest 4 is a threaded stem 18 engaged by a nut 20 which is mounted between lugs formed on another slide 22 movable along the guideways 12 on the carrier 14. Accordingly the toe rest may be adjusted by the nut 20 in directions heightwise of the shoe relatively to the block 6, as may be required to position shoes of different styles in proper relation to the lasting devices hereinafter described. Extending through pins 24 and 26 which are mounted to turn respectively in the two slides 10 and 22 is a spindle 28 provided with right and left threads in engagement respectively with corresponding threads in the two pins, so that by turning the spindle the two slides 10 and 22 may be adjusted toward or from each other. A hand wheel 30 fast on the spindle is provided for turning it. Rotatably mounted on a stud 32 on the carrier 14 is a lever 34 (Fig. 2) the opposite ends of which are connected respectively by links 36 and 38 to the slides 10 and 22, so that when these slides are adjusted toward or from each other by the spindle 28 they are maintained at all times at equal distances from the stud 32. This serves to insure that when the slides are adjusted for shoes of different sizes the ball line of each shoe will occupy substantially the same position forwardly and rearwardly of the machine, as is desirable in order to position the shoes in proper relation to the lasting devices.

Since lasts of different styles and sizes vary in height, the machine is provided with special

means for positioning each shoe with its bottom at substantially the same height for the operation of the lasting devices thereon. For this purpose, in the use of the machine on each shoe, a height gage 40 which is arranged for contact with the bottom of the shoe at its ball portion is moved downwardly to a fixed predetermined position and the shoe is forced upwardly until it contacts with the gage, the movement of the gage and the movement of the shoe in the machine herein shown being effected by depression of a single treadle 42. The gage 40 is supported over the shoe on one end of an arm 44 which is fast at its other end on a pin 46 rotatably mounted in a bracket 48 on the frame of the machine, and also fast on this pin is an arm 50 pivotally connected to a link 52. This link is pivotally connected to another link 54 mounted to swing about a pin 56 on the frame, and integral with the link 54 is an arm 58 connected by a link 60 to the rear end of a laterally offset arm of the treadle 42, this treadle being mounted to swing about a fulcrum rod 62 supported as hereinafter described. It will thus be seen that when the treadle is depressed against the resistance of a spring 64 it acts to swing the two links 52 and 54 from the positions in which they are shown in Fig. 1 to positions in alignment with each other, as illustrated in Fig. 3, such movement of the links being limited by engagement of the link 54 with a pin 66 on the frame. In this manner the gage 40 is swung from its initial retracted position, where it does not interfere with the mounting of the work on the work support, into position to determine the proper height of the shoe by engagement with the bottom of the ball portion of the shoe. It will be evident that by reason of the character of the means hereinbefore described for adjusting the slides 10 and 22 for shoes of different sizes, corresponding portions of such different shoes will be presented under the gage. The gage 40 is carried by a stem 68 threaded in the arm 44, so that by turning the stem the gage may be adjusted relatively to the arm in directions heightwise of the shoe to vary the height at which the shoe is presented, the stem being held in adjusted position by a lock nut 70.

To carry the shoe heightwise into contact with the gage 40 the shoe support is vertically movable, the carrier 14 being provided with downwardly extending rods 72 and 74 slidably mounted in guides 76 on the frame. The carrier is connected by a link 78 to one arm of a lever 80 pivotally mounted on a pin 82 on the frame, and the other arm of this lever is arranged to be engaged and operated by a pin 84 carried by the treadle 42, the arm having a recess 86 therein to receive the pin. When the parts are in their initial positions the carrier 14 is in a lower position than illustrated in Fig. 1 with bosses 88 thereon in engagement with the upper ends of the guides 76 and with the front arm of the lever 80 raised so that the pin 84 is in the recess 86. When the operator depresses the treadle 42 the gage 40 is moved downwardly to its operative position, determined by engagement of the pin 66 with the link 54, before the shoe has been moved upwardly far enough to contact with the gage. In order to permit such further movement of the treadle 42 as to raise the shoe into contact with the gage, the fulcrum rod 62 which supports the treadle is mounted on a link 90 which may swing downwardly about a pin 92 on the frame against the resistance of a spring 75

94, the link being held upwardly by this spring against a fixed stop 96 when the treadle is initially depressed to move the gage 40 into operative position. It will thus be seen that the 5 treadle has a yielding fulcrum which permits it to swing about its connection with the link 60 to impart such further movement to the lever 80 as is required to bring the shoe into contact with the gage. For holding the shoe 10 support at the limit of its upward movement determined by the gage 40, a pawl 98 is pivotally mounted on a pin 100 on the front end of the lever 80 and cooperates with ratchet teeth formed on a plate 102 fast on the frame 15 to prevent return movement of the lever 80 when the operator releases the treadle. A torsion spring 104 carried by the lever 80 holds the pawl in engagement with the teeth. After positioning the shoe at the proper height by depression 20 of the treadle the operator releases the treadle to permit the gage 40 to be moved upwardly away from the shoe so as to avoid interference with the lasting devices. To permit the shoe support to be lowered by gravity to its initial position after the lasting operation the pawl 98 is 25 swung by the operator away from the ratchet teeth by depression of a treadle 106 which operates a crank arm 108 connected by a link 110 to the lower end of the pawl.

30 For lasting the sides of a shoe positioned and supported as above described the machine herein shown is provided with different pairs of lasting devices movable to lay the margin of the upper inwardly over an insole on the last at the opposite 35 sides of the forepart, shank and waist portions of the shoe, respectively, the forepart-lasting devices being designated generally by the reference characters 112 (Fig. 2), the shank-lasting devices by the reference characters 114, and the waist-lasting 40 devices by the reference characters 116. Each of the several lasting devices comprises a group of overlaying members or wipers 118 arranged in a series lengthwise of the edge of the shoe bottom for wiping the margin of the upper over the insole. These wipers, except for differences hereinafter referred to, are all alike, and each of them 45 consists of a leaf spring reversely curved a plurality of times, as illustrated in Fig. 4, to provide a series of inwardly and outwardly extending portions 120 spaced from one another heightwise of the shoe to increase the yieldability of the wiper. The upper-engaging portions of the wipers of each group are in substantially contiguous 50 relation to one another, but the wipers decrease progressively in width heightwise of the shoe in a direction away from the shoe bottom to permit them to be relatively adjusted as hereinafter described. The wipers 118 of the forepart-lasting devices 112, herein illustrated as four in number 55 at each side of the shoe, are fast on the inner end portions of outwardly extending arms 122, and the two groups of arms are supported by holders 124 which are carried by hand levers 126 both mounted to swing about a vertical rod 128 supported by the frame in a location opposite the toe-end face of the shoe. Each group of arms 122 is secured adjustably to its holder 124 by clamping blocks 130 (Fig. 7) movably mounted in a guideway in the holder and recessed to engage spherical bosses 132 on the sides of the outer end portions of the arms, the blocks being operated to clamp the arms firmly by one or the other of two screws 134 and 135 threaded in the holder. It will thus be seen that the arms 60 65 70 75 122 are mounted for universal adjusting move-

ments and that by swinging them heightwise of the shoe relatively to one another and turning them about axes extending transversely of the edge of the shoe bottom lengthwise of the wipers 118 mounted thereon the wipers may be adjusted 5 to conform substantially to the lengthwise contour of the portions of the shoe bottom on which they operate, the clamping blocks 130 being shaped to permit the required adjusting movements of the arms. Further to assist in adjusting the forepart-lasting devices in proper relation to shoes of different styles, each of the holders 124 may be swung relatively to its supporting lever 126 about an axis extending laterally of the shoe, the holder being provided for purposes of 10 this adjustment with a stem 136 rotatable in a split bearing 138 on the lever 126 and held securely in adjusted position by a screw 140 which contracts this bearing. The two levers 126 are so formed that while the lasting devices 112 15 supported thereon are at substantially the same height, the hub of the left-hand lever underlies the hub of the right-hand lever on the rod 128, as shown in Fig. 1, the levers being held against any upward movement by a portion of the bracket 20 25 30 35 40 45 50 55 60 65 70 75 80 85 90 95 100 105 110 115 120 125 130 135 140 two wipers 118 which are located nearest the heel end of the shoe may be rendered inoperative by suitable adjustment of the corresponding arms 154.

- 5 The wipers 118 of the waist-lasting devices 116 which, as herein shown, are three in number at each side of the shoe, are arranged to wipe the margin of the upper inwardly between the portions operated upon by the shank-lasting devices 114 and the portions operated upon by the forepart-lasting devices. These waist-lasting devices are supported and operated by hand levers 156 which are mounted for swinging movements about vertical studs 158 fastened to the frame 10 in locations substantially opposite the sides of the toe of the shoe and spaced substantial distances from the shoe widthwise thereof. The hand levers 156 extend to positions where the operator at the front of the machine can conveniently manipulate them, and they are of angular shape, as illustrated in Fig. 2, to position the two groups of wipers in an angular relation to each other corresponding in general to the angular relation of the opposite side edges 15 of the shoe bottom extending heelwardly of the ball line. These two groups of wipers 118 are mounted on arms 160 which are like the arms 122 of the forepart-lasting devices except that they are of angular shape as illustrated in Fig. 2 for purposes of clearance. The arms 160 are adjustable in the same manner as the arms 122, and they are clamped in adjusted positions by means (Fig. 6) of the same character as in the case of the forepart-lasting devices. Each group 20 of arms 160 and its clamping means are supported by a holder 162 provided with a stem 164 rotatable in a split bearing 166 on the lever 156 to assist in adjusting the wipers in proper relation to the shoe, the holder being secured in 25 an adjusted position by a screw 168 which contracts the split bearing 166. It will be evident that the studs 158 about which the levers 156 are swung are located in such relation to the shoe that the wipers 118 of the waist-lasting devices 30 move in paths so curved that they have substantial components of movement lengthwise of the shoe toward its toe end, as is appropriate by reason of the fact that the side edges of the shoe bottom where these wipers operate curve inwardly from the ball line toward the shank portion of the shoe.
- It is assumed that in the use of the machine herein shown the shank-lasting devices 114 will be moved inwardly over the shoe bottom before the waist-lasting devices 116, and in order that the margin of the upper may be wiped inwardly in a satisfactory manner at the junction of the shank and waist portions of the shoe, those wipers 118 of the shank-lasting devices which 35 are located nearest the toe end of the shoe are so formed that when they are over the shoe bottom their edges 170 (Fig. 2) which are next to the waist-lasting wipers are substantially tangential to the paths of movement of the latter. By reason of this construction the margin of the upper which lies next to the shank-lasting wipers at each side is wiped inward substantially throughout its width, and there is, moreover, no danger of wrinkling or pinching 40 the margin of the upper between the waist-lasting wipers and the shank-lasting wipers. Furthermore, those wipers 118 of the waist-lasting devices which are nearest the toe end of the shoe are, for a similar purpose, so formed that the portions 45 172 of their edges next to the fore-

part-lasting wipers are substantially tangential to the paths of movement of the latter. At the end of the operative movements of all the lasting devices the wipers 118 are accordingly in substantially continuous engagement with the margin of the upper all along the opposite sides of the shoe bottom from the toe portion to the heel portion of the shoe. It is contemplated that preferably the wipers will be moved inwardly to substantially the same positions regardless of 10 the size of the shoe operated upon.

Before a shoe is presented to the machine it will ordinarily have been pulled over and may or may not have been lasted at the toe and heel ends, the shoe herein shown being one the opposite ends of which are to be lasted after it leaves the machine. The operator mounts the last and shoe on the work support, tipping the last pin 2 against the resistance of the spring 16 by the action of the last thereon to permit the forepart 15 of the shoe to be positioned over the toe rest 4, the spring then holding the shoe pressed down on the toe rest by its tendency to tip the pin in the opposite direction. By depression of the treadle 42 the operator then moves the height 20 gage 40 downwardly to the limit determined by engagement of the pin 66 with the link 54 and raises the work support to bring the bottom of the shoe into contact with the gage, such contact being effected by further movement of the 25 treadle after the gage has arrived at the limit of its movement, as permitted by the yieldable fulcrum support on which the treadle is mounted. The operator then releases the treadle to permit it to be returned to its initial position 30 and the gage 40 to be retracted from the shoe by the action of the spring 64, the work support, however, being locked against return movement by the pawl 98. Thereafter the operator swings the levers 142 inwardly to cause the 35 shank-lasting devices 114 to wipe the margin of the upper inwardly over the insole at both sides of the shoe simultaneously, or first at one side and then at the other side, as may be desired. Next, while the shank wipers are over the shoe 40 bottom, the operator swings the levers 156 to operate in a similar manner the waist-lasting devices 116, and while the wipers of these devices are over the shoe bottom he swings the levers 126 to operate the forepart-lasting devices 112. 45 Concurrently with the use of any of these lasting devices the operator may, if desired, use hand pincers to apply a pull to the margin of the upper. A suitable adhesive will have been previously applied to the shoe for securing the 50 margin of the upper materials to the insole, and accordingly the margin adheres to the insole when it is wiped inwardly in the manner above described, the wipers 118 by reason of their construction being sufficiently yieldable to insure 55 substantially uniform pressure on the margin of the upper all along the forepart, waist and shank portions of the shoe bottom even though their supporting arms may not have been previously adjusted to position the wipers in exact 60 conformity to the lengthwise contour of the shoe bottom. After having thus lasted the sides of the shoe the operator retracts first the forepart-lasting devices, then the waist-lasting devices, and thereafter the shank-lasting devices from 65 over the shoe bottom, depresses the treadle 106 to unlock the work support and permit it to return to its initial position, and then removes the shoe from the machine.

Having described the invention, what I claim 70

as new and desire to secure by Letters Patent of the United States is:

- 5 1. In a lasting machine, the combination with a support for a last and its shoe materials, of forepart-lasting devices movable to lay the margin of the shoe upper inwardly over the bottom of the last at the opposite sides of the forepart, shank-lasting devices movable to lay the margin of the upper inwardly at the sides of the shank portion of the shoe, and waist-lasting devices movable laterally of the shoe in different directions than said forepart and shank-lasting devices with predetermined components of movement lengthwise of the shoe toward its toe end to lay the margin of the upper inwardly at the sides of the waist portion of the shoe.
- 10 2. In a lasting machine, the combination with a support for a last and its shoe materials, of forepart-lasting devices movable to lay the margin of the shoe upper inwardly over the bottom of the last at the opposite sides of the forepart, shank-lasting devices movable to lay the margin of the upper inwardly at the sides of the shank portion of the shoe, and waist-lasting devices movable to lay the margin of the upper inwardly at the sides of the waist portion of the shoe, said waist-lasting devices being thus movable laterally of the shoe relatively to the forepart and shank-lasting devices in predetermined paths curved about axes extending heightwise of the shoe with components of movement lengthwise of the shoe toward its toe end.
- 15 3. In a lasting machine, the combination with a support for a last and its shoe materials, of forepart-lasting devices movable to lay the margin of the shoe upper inwardly over the bottom of the last at the opposite sides of the forepart, shank-lasting devices movable to lay the margin of the upper inwardly at the sides of the shank portion of the shoe, and waist-lasting devices movable to lay the margin of the upper inwardly at the sides of the waist portion of the shoe, each of the several devices being thus movable relatively to the others about an axis extending heightwise of the shoe.
- 20 4. In a lasting machine, the combination with a support for a last and its shoe materials, of forepart-lasting devices movable each about an axis located substantially opposite the toe-end face of the last to lay the margin of the shoe upper inwardly over the bottom of the last at the opposite sides of the forepart, shank-lasting devices movable each about an axis located substantially opposite the heel-end face of the last to lay the margin of the upper inwardly at the sides of the shank portion of the shoe, and waist-lasting devices movable about axes located substantially opposite the sides of the toe to lay the margin of the upper inwardly at the sides of the waist portion of the shoe.
- 25 5. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, and different pairs of hand levers movable to operate respectively said different pairs of lasting devices.
- 30 6. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, and different pairs of hand levers movable to operate respectively said different pairs of lasting devices.
- 35 7. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, a pair of hand levers movable each about an axis located substantially opposite the toe-end face of the shoe to operate the forepart-lasting devices, another pair of hand levers movable each about an axis located substantially opposite the heel-end face of the shoe to operate the shank-lasting devices, and a third pair of hand levers movable about axes located substantially opposite the sides of the toe to operate the waist-lasting devices.
- 40 8. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, each of said pairs of lasting devices being thus movable independently of the others and comprising at each side of the shoe a plurality of overlaying members yieldable relatively to one another heightwise of the shoe in response to pressure of the shoe thereon.
- 45 9. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, each of said pairs of lasting devices being thus movable independently of the others and comprising at each side of the shoe a plurality of overlaying members adjustable relatively to one another in accordance with the lengthwise contour of the bottom of the shoe.
- 50 10. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, each of said pairs of lasting devices being thus movable independently of the others and comprising at each side of the shoe a plurality of wipers yieldable relatively to one another heightwise of the shoe in response to pressure of the shoe thereon and relatively adjustable preliminarily in accordance with the lengthwise contour of the bottom of the shoe.
- 55 11. In a lasting machine, the combination with a support for a last and its shoe materials, of forepart-lasting devices movable to lay the margin of the shoe upper inwardly over the bottom of the last at the opposite sides of the forepart, levers supporting said devices and movable each about an axis extending heightwise of the shoe thus to operate the devices, waist-lasting devices movable to lay the margin of the upper inwardly at the opposite sides of the waist portion of the shoe, and other levers supporting said waist-lasting devices and movable about axes extending heightwise of the shoe to impart to said devices their operative movements in curved paths with components of movement toward the toe end of
- 60 70 75

respectively, and different pairs of levers arranged to support respectively said different pairs of lasting devices and movable about axes extending heightwise of the shoe to operate said devices.

5 10 15 20 25 30 35 40 45 50 55 60 65 70 75

7. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, a pair of hand levers movable each about an axis located substantially opposite the toe-end face of the shoe to operate the forepart-lasting devices, another pair of hand levers movable each about an axis located substantially opposite the heel-end face of the shoe to operate the shank-lasting devices, and a third pair of hand levers movable about axes located substantially opposite the sides of the toe to operate the waist-lasting devices.

8. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, each of said pairs of lasting devices being thus movable independently of the others and comprising at each side of the shoe a plurality of overlaying members yieldable relatively to one another heightwise of the shoe in response to pressure of the shoe thereon.

9. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, each of said pairs of lasting devices being thus movable independently of the others and comprising at each side of the shoe a plurality of overlaying members adjustable relatively to one another in accordance with the lengthwise contour of the bottom of the shoe.

10. In a lasting machine, the combination with a support for a last and its shoe materials, of different pairs of lasting devices movable to lay the margin of the shoe upper inwardly over the bottom of the last at the opposite sides of the forepart, shank and waist portions of the shoe respectively, each of said pairs of lasting devices being thus movable independently of the others and comprising at each side of the shoe a plurality of wipers yieldable relatively to one another heightwise of the shoe in response to pressure of the shoe thereon and relatively adjustable preliminarily in accordance with the lengthwise contour of the bottom of the shoe.

11. In a lasting machine, the combination with a support for a last and its shoe materials, of forepart-lasting devices movable to lay the margin of the shoe upper inwardly over the bottom of the last at the opposite sides of the forepart, levers supporting said devices and movable each about an axis extending heightwise of the shoe thus to operate the devices, waist-lasting devices movable to lay the margin of the upper inwardly at the opposite sides of the waist portion of the shoe, and other levers supporting said waist-lasting devices and movable about axes extending heightwise of the shoe to impart to said devices their operative movements in curved paths with components of movement toward the toe end of

the shoe in angular relation to the directions of movement of the forepart-lasting devices.

12. In a lasting machine, the combination with a support for a last and its shoe materials, of 5 forepart-lasting devices movable to lay the margin of the shoe upper inwardly over the bottom of the last at the opposite sides of the forepart, waist-lasting devices movable to lay the margin of the upper inwardly at the opposite sides of the 10 waist portion of the shoe, and supports for said waist-lasting devices pivotally mounted for swinging movements about fixed axes extending heightwise of the shoe to impart to said devices their operative movements in curved paths with 15 components of movement toward the toe end of the shoe in angular relation to the directions of movement of the forepart-lasting devices.

13. In a lasting machine, the combination with a support for a last and its shoe materials, of 20 forepart-lasting devices movable to lay the margin of the shoe upper inwardly over the bottom of the last at the opposite sides of the forepart, and waist-lasting devices movable laterally of the 25 shoe in different directions than said forepart-lasting devices with predetermined components of movement toward the toe end of the shoe to lay the margin of the upper inwardly at the opposite sides of the waist portion of the shoe, each of the several devices comprising a plurality of 30 overlaying members yieldable relatively to one another heightwise of the shoe in response to pressure of the shoe thereon.

14. In a lasting machine, the combination with a support for a last and its shoe materials, of 35 forepart-lasting devices movable to lay the margin of the shoe upper inwardly over the bottom of the last at the opposite sides of the forepart, and waist-lasting devices movable laterally of the 40 shoe in different directions than the forepart-lasting devices with predetermined components of movement toward the toe end of the shoe to lay the margin of the upper inwardly at the opposite sides of the waist portion of the shoe, each of the several devices comprising a plurality of 45 overlaying members adjustable relatively to one another in accordance with the lengthwise contour of the bottom of the shoe.

15. In a lasting machine, the combination with a support for a last and its shoe materials, of 50 shank-lasting devices movable to lay the margin of the shoe upper inwardly over the bottom of the last at the opposite sides of the shank portion of the shoe, and waist-lasting devices movable laterally of the shoe in different directions 55 than the shank-lasting devices with predetermined components of movement lengthwise of the shoe toward its toe end to lay the margin of the upper inwardly at the opposite sides of the waist portion of the shoe.

16. In a lasting machine, the combination with a support for a last and its shoe materials, of 60 shank-lasting devices movable each about an axis extending heightwise of the shoe to lay the margin of the shoe upper inwardly over the bottom of the last at the opposite sides of the shank portion of the shoe, and waist-lasting devices movable laterally of the shoe in different directions than the shank-lasting devices about 65 axes extending heightwise of the shoe with predetermined components of movement lengthwise of the shoe toward its toe end to lay the margin of the upper inwardly at the opposite sides of the waist portion of the shoe.

17. In a lasting machine, the combination with 70 a support for a last and its shoe materials, of

shank-lasting devices movable to lay the margin of the shoe upper inwardly over the bottom of the last at the opposite sides of the shank portion of the shoe, and waist-lasting devices movable laterally of the shoe in different directions 5 than the shank-lasting devices with components of movement lengthwise of the shoe toward its toe end to lay the margin of the upper inwardly at the opposite sides of the waist portion of the shoe, said shank-lasting devices comprising 10 wipers arranged to lie in substantially contiguous relation to the waist-lasting devices when the several devices are over the shoe bottom and having edges arranged to extend in substantially tangential relation to the paths of movement of 15 the waist-lasting devices.

18. In a lasting machine, the combination with a support for a last and its shoe materials, of 20 shank-lasting devices movable each about an axis extending heightwise of the shoe in a location substantially opposite the heel-end face of the shoe to lay the margin of the shoe upper inwardly over the bottom of the last at the opposite sides of the shank portion of the shoe, and waist-lasting devices movable about axes extending 25 heightwise of the shoe in locations substantially opposite the sides of the toe at substantial distances from the shoe to lay the margin of the upper inwardly at the opposite sides of the waist portion of the shoe.

19. In a lasting machine, the combination with a support for a last and its shoe materials, of 30 different pairs of lasting devices movable to lay the margin of the shoe upper inwardly over the bottom of the last at the opposite sides of the shank and the waist portions of the shoe 35 respectively, and different pairs of levers arranged to support respectively said different pairs of lasting devices and movable about axes extending heightwise of the shoe to operate said devices. 40

20. In a lasting machine, the combination with a support for a last and its shoe materials, of shank-lasting devices movable to lay the margin of the shoe upper inwardly over the bottom of the last at the opposite sides of the shank 45 portion of the shoe, and waist-lasting devices movable to lay the margin of the upper inwardly at the opposite sides of the waist portion of the shoe with components of movement lengthwise of the shoe toward its toe end relatively to the shank-lasting devices, each of the several devices comprising a plurality of overlaying members 50 yieldable relatively to one another heightwise of the shoe in response to pressure of the shoe thereon.

21. In a lasting machine, the combination with a support for a last and its shoe materials, of shank-lasting devices movable to lay the margin of the shoe upper inwardly over the bottom of the last at the opposite sides of the shank portion of the shoe, and waist-lasting devices movable to lay the margin of the upper 55 inwardly at the opposite sides of the waist portion of the shoe with components of movement lengthwise of the shoe toward its toe end relatively to the shank-lasting devices, each of the several devices comprising a plurality of overlaying members adjustable relatively to one another in accordance with the lengthwise contour of the bottom of the shoe.

22. In a lasting machine, the combination with a support for a last and its shoe materials, of waist-lasting devices movable to lay the margin of the shoe upper inwardly over the bottom of the last at the opposite sides of the waist por- 70

tion of the shoe, and supports for said devices pivotally mounted for swinging movements laterally of the shoe about fixed axes extending heightwise of the shoe to impart to said devices their operative movements in curved paths with components of movement toward the toe end of the shoe.

23. In a lasting machine, the combination with a support for a last and its shoe materials, of waist-lasting devices movable to lay the margin of the shoe upper inwardly over the bottom of the last at the opposite sides of the waist portion of the shoe, and hand levers supporting said devices and mounted for swinging movements about axes extending heightwise of the shoe to impart to the devices their operative movements in curved paths with components of movement toward the toe end of the shoe.

24. In a lasting machine, the combination with a support for a last and its shoe materials, of means for wiping the margin of the shoe upper inwardly over the bottom of the last, said wiping means comprising a plurality of upper-engaging leaf springs arranged in a series lengthwise of the edge of the shoe bottom and each reversely curved a plurality of times to provide a series of inwardly and outwardly extending portions spaced from one another heightwise of the shoe, the several springs being adjustable relatively to one another in accordance with the contour of the shoe bottom.

25. In a lasting machine, the combination with a support for a last and its shoe materials, of means for wiping the margin of the shoe upper inwardly over the bottom of the last, said wiping means comprising a plurality of upper-engaging leaf springs arranged in a series lengthwise of the edge of the shoe bottom and each reversely curved a plurality of times to provide a series of inwardly and outwardly extending portions spaced from one another heightwise of the shoe, the several springs being adjustable relatively to one another about axes extending lengthwise thereof transversely of the edge of the shoe bottom and being so formed as to decrease progressively in width heightwise of the shoe in directions away from the shoe bottom.

26. In a lasting machine, the combination with a support for a last and its shoe materials, of means for wiping the margin of the shoe upper inwardly over the bottom of the last, said wiping means comprising a plurality of arms arranged in a series lengthwise of the edge of the shoe bottom and each having at one end thereof a leaf spring arranged to act as a wiper on the margin of the upper and reversely curved a plurality of times to provide a series of inwardly and outwardly extending portions spaced from one another heightwise of the shoe, the several arms being individually adjustable to position said springs in a relation to one another corresponding substantially to the contour of the shoe bottom.

27. In a lasting machine, a wiper for wiping the margin of an upper inwardly over the bottom of a last, said wiper comprising a leaf spring reversely curved a plurality of times to provide a series of inwardly and outwardly extending portions spaced from one another heightwise of the shoe.

28. In a lasting machine, the combination with lasting means movable to lay the margin of an upper inwardly over the bottom of a last, of a work support arranged to receive the last and its shoe materials, a gage for determining the

position of the last and shoe heightwise relatively to said lasting means by contact with the bottom of the shoe, said gage being movable from an initial retracted position into gaging position, a member movable by the operator to impart such movement to the gage, and mechanism for also moving the work support to carry the shoe heightwise into contact with the gage by movement of said member.

29. In a lasting machine, the combination with lasting means movable to lay the margin of an upper inwardly over the bottom of a last, of a work support arranged to receive the last and its shoe materials, a gage for determining the position of the last and shoe heightwise relatively to said lasting means by contact with the bottom of the shoe, said gage being movable from an initial retracted position into gaging position, a member movable by the operator to impart such movement to the gage, mechanism for also moving the work support to carry the shoe heightwise into contact with the gage by movement of said member, means for retracting the gage from the shoe upon reverse movement of said member prior to the operation of said lasting means on the shoe, and a device for locking the work support against reverse movement when the gage is thus retracted.

30. In a lasting machine, the combination with lasting means movable to lay the margin of an upper inwardly over the bottom of a last, of a work support arranged to receive the last and its shoe materials, a gage for determining the position of the last and shoe heightwise relatively to said lasting means by contact with the bottom of the shoe, a gage carrier mounted for swinging movement to carry the gage downwardly from an initial retracted position into gaging position, a treadle movable by the operator thus to operate said gage carrier, and mechanism arranged to be operated by said treadle to raise the work support and thus to move the shoe into contact with the gage.

31. In a lasting machine, the combination with lasting means movable to lay the margin of an upper inwardly over the bottom of a last, of a work support arranged to receive the last and its shoe materials, a gage for determining the position of the last and shoe heightwise relatively to said lasting means by contact with the bottom of the shoe, a treadle for moving said gage downwardly from an initial retracted position into gaging position, mechanism arranged to be operated by said treadle to raise the work support and thus to move the shoe into contact with the gage, means for retracting the gage from the shoe upon release of the treadle by the operator prior to the operation of said lasting means on the shoe, and a device for locking the work support against downward movement when the gage is thus retracted.

32. In a lasting machine, the combination with lasting means movable to lay the margin of an upper inwardly over the bottom of a last, of a work support arranged to receive the last and its shoe materials, a gage for determining the position of the last and shoe heightwise relatively to said lasting means by contact with the bottom of the shoe, said gage being movable in a direction heightwise of the shoe from an initial retracted position into gaging position and the work support being movable in the opposite direction to carry the shoe into contact with the gage, and a member movable by the operator for imparting such movements to the gage and the

work support and for completing the movement of the work support after the gage has completed its movement.

33. In a lasting machine, the combination with lasting means movable to lay the margin of an upper inwardly over the bottom of a last, of a work support arranged to receive the last and its shoe materials, a gage for determining the position of the last and shoe heightwise relatively to said lasting means by contact with the bottom of the shoe, a treadle and mechanism operated thereby for moving said gage downwardly from an initial retracted position into gaging position, means for limiting the movement of said mechanism to determine the position of the gage, mechanism arranged to be operated also by said treadle to raise the work support and thus to move the shoe into contact with the gage, and a yieldable fulcrum for said treadle to permit further movement of the treadle thus to raise the work support after the gage has arrived in its gaging position.
34. In a lasting machine, the combination with lasting means movable to lay the margin of an

upper inwardly over the bottom of a last, of a work support arranged to receive the last and its shoe materials, a gage for determining the position of the last and shoe heightwise relatively to said lasting means by contact with the bottom of the shoe, a treadle and mechanism operated thereby for moving said gage downwardly from an initial retracted position into gaging position, means for limiting the movement of said mechanism to determine the position of the gage, mechanism including a lever arranged to be operated also by said treadle to raise the work support and thus to move the shoe into contact with the gage, a yieldable fulcrum for said treadle to permit the movement of the work support to be completed by further movement of the treadle after the gage has arrived in its gaging position, the treadle being reversely movable relatively to said lever when released by the operator to permit the gage to be retracted from the shoe, and means for preventing downward movement of the work support when the treadle is thus released.

ERASTUS E. WINKLEY.
